SHOESHINE STAND

Orville A. Blalack, Teaneck, N.J.

Application April 9, 1958, Serial No. 50,398

Term of patent 14 years

(Cl. D9—2)

Fig. 1 is a front perspective view of a shoeshine stand, showing my new design;

Fig. 2 is a reduced elevational view thereof as seen from the opposite side of Fig. 1 with the drawer in closed position; and

Fig. 3 is a rear elevational view of Fig. 2.

I claim:

The ornamental design for a shoeshine stand, substantially as shown.
